Primary Examiner — Nicole C Shiflet*Assistant Examiner* — Danielle Nichole Bowly(74) *Attorney, Agent, or Firm* — NIXON & VANDERHYDE(57) **CLAIM**

The ornamental design for a toner container, as shown and described.

DESCRIPTION

FIG. 1 is a front perspective view of front, top and right side of a toner container showing our new design;

FIG. 2 is a rear perspective view of rear, top and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The smaller broken lines shown in the figures depict portions that form no part of the claimed design.

The larger broken lines in the figures represent perforations on the toner container that do form part of the claimed design.

1 Claim, 7 Drawing Sheets(56)
